US0D1040502S

(12) **United States Design Patent** (10) Patent No.: **US D1,040,502 S**
(45) Date of Patent: ** Sep. 3, 2024

(54) **INSOLE**

(71) Applicants: **Zhuangli Qin**, Xiaogan (CN);
Zhengjun Lv, Yichang (CN)

(72) Inventors: **Zhuangli Qin**, Xiaogan (CN);
Zhengjun Lv, Yichang (CN)

(**) Term: **15 Years**

(21) Appl. No.: **35/519,787**

(22) Filed: **Dec. 21, 2023**

(80) **Hague Agreement Data**

Int. Filing Date: **Dec. 21, 2023**

Int. Reg. No.: **DM/234559**

Int. Reg. Date: **Dec. 21, 2023**

Int. Reg. Pub. Date: **Jan. 26, 2024**

(51) LOC (14) Cl. **02-04**

(52) U.S. Cl.

USPC **D2/961**

(58) **Field of Classification Search**

USPC D2/914, 915, 947, 951, 961, 968
